UNITED STATES PATENT OFFICE.

EDWARD A. HALBLEIB, OF ROCHESTER, NEW YORK, ASSIGNOR TO NORTH EAST ELECTRIC COMPANY, OF ROCHESTER, NEW YORK, A CORPORATION OF NEW YORK.

ELECTRIC SWITCH.

1,082,694.

Specification of Letters Patent.

Patented Dec. 30, 1913.

Application filed November 29, 1912. Serial No. 734,140.

To all whom it may concern:

Be it known that I, EDWARD A. HALBLEIB, a citizen of the United States, and resident of Rochester, in the county of Monroe and State of New York, have invented certain new and useful Improvements in Electric Switches, of which the following is a specification.

This invention relates to electric switches, of the type disclosed in the patent granted to me No. 1,010,753, dated December 5, 1911, in which a series of switch-plugs are longitudinally movable through the walls of a casing, the casing inclosing contact-devices, coöperating with the plugs, and locking-mechanism for locking the plugs in either their upper or lower positions.

One object of the present invention is to simplify the construction and facilitate the manufacture of switches of the type in question, and particularly to avoid the necessity of partitions or bearing-members in the casing to support the locking-plate which coöperates with the plugs. To this end I so form the locking-plate itself as to provide bearing-members, which engage the inner surfaces of the walls of the casing, and thus guide and support the locking-plate, and also stiffen it longitudinally.

Another object of the invention is to provide the switch with contact-members so constructed and arranged that the switch may be used conveniently in a three-wire electric system, each plug being adapted to simultaneously connect or disconnect three fixed contact-members. To this end I employ the form and arrangement of contact-devices hereinafter described.

In the accompanying drawings:—Figure 1 is a front-elevation of a switch embodying the present invention, with the front-portion of the casing broken away to show the interior mechanism; Fig. 2 is a section, looking downwardly, on the line 2—2 in Fig. 1; Fig. 3 is a section on the line 3—3 in Fig. 1, looking from left to right; and Fig. 4 is a section on the line 4—4 in Fig. 1, looking from right to left.

In general construction and arrangement the switch illustrated in the drawings is similar to that of my said patent. It is provided with a base plate 6 of insulating material, which may be fastened against the surface upon which the switch is to be mounted. The casing of the switch, how-

ever, instead of being provided with partitions and bearing-members as in said patent, consists of a simple sheet-metal member of generally-rectangular form, drawn from a single piece of sheet-metal. This casing 60 comprises a flat front 7, flat end-walls 8 and 9, and flat upper and lower walls 10 and 11, respectively. Around the entire periphery of the casing it is provided with a flange, having an outwardly-extending portion 12 65 and a rearwardly-extending portion 13. This flange provides a peripheral shoulder or seat adapted to engage the margin of the base-plate 6, and the flange is drawn closely against the base-plate by means of 70 bolts 14 passing through the casing and the base-plate and fixed by nuts 15. These bolts are also provided with threaded rear-exten- 75 sions 16 and nuts 17, by which the switch may be secured to a dash-board or other surface.

The switch-plugs, of which four are shown in the drawings, are arranged to slide vertically through alining perforations in the upper and lower walls 10 and 11 of the cas- 80 ing. Each plug has a central metal rod 18 provided with buttons or heads 19 and 20 on its upper and lower end, respectively. Near its upper portion each plug is pro- 85 vided with a bushing 21 of insulating-ma- 90 terial, while below this bushing, and in- 95 sulated from the rod 18, is a metal sleeve 22, constituting a contact-piece or conductor. This contact-piece is insulated, at its lower end, by a bushing 23, and below this bush- 95 ing is a metal portion 25 provided with upper and lower annular slots 26 and 27, respectively. These slots provide locking- 95 shoulders or abutments, which coöperate with the locking-plate.

The locking-plate 28 consists of an elongated sheet-metal member arranged horizontally a short distance above the lower wall 11 of the casing. Each plug passes through an opening 29 in the locking-plate, and these openings, as shown in Fig. 2, are of a sub- 100 stantially key-hole shape, so that in one position of the plate each plug may pass freely through the corresponding opening, while in the other position of the plate, as 105 shown in Fig. 2, the plug is locked against longitudinal movement by the engagement of its locking-abutments with the upper and lower surface of the plate adjacent the narrow end of the opening 29.

To support the locking-plate in operative position within the casing, and to guide it in and restrict it to longitudinal horizontal movements, the plate is provided with lateral downwardly-extending flanges 30 which have bearing-extensions 31 at their ends which rest upon the lower wall 11 of the casing. The flanges 30 serve to stiffen the plate longitudinally and support it against pressure exerted manually upon the switch-plugs when they are locked in position. To prevent the locking-plate from rising with the plugs it has upwardly-bent extremities 32 and 33, which project into engagement with the upper wall 10 of the casing. These projections are laterally extended at points 34, so as to engage the front wall 7, and the base-plate 6, and thus support the locking-plate laterally. By its engagement with the casing-walls and the base-plate, as just described, the locking-plate is restrained to longitudinal horizontal movement, and the projections 32 and 33 also coöperate with the means for so moving the locking-plate. The projection 33 is engaged by a spring 35 which normally holds the locking-plate in its left-hand or operative position. In this position the projection 32 rests against a U-shaped member 38, which is fastened within the left-hand end of the casing by means of screws 37, passing through the lower wall 11 and threaded into a block 36 which lies within the member 38. The member 38 and the front-wall 7 of the casing are provided with alining key-holes and with a rotatable cleft sleeve 39 adapted to receive the shank of a key 40. The wards 41 of the key enter a vertical slot 42 in the block 36, and coöperate with wards 43 also formed in the block. When the key is inserted and is given a three-quarter turn to the right its wards engage the projection 32 on the locking-plate and force the plate to the right, against the opposition of the spring 35, thus unlocking the switch-plugs. The rotation of the key is arrested by engagement with a flange 44 on the block 36, in a position in which it may be left to hold the locking-plate in unlocked position. Coöoperating with each switch-plug is a pair of contact-springs 45, each of these springs being supported by a supplemental spring 46. These springs are clamped in shallow slots in the base-plate 6, by the heads 47 of studs 48 which pass through the base-plate and through binding-posts 49, so as to connect the springs electrically with terminals 50 adapted to receive electric conductors. When the plugs are in depressed position the contact-springs 45 of each pair engage one of the insulating-bushings 21, but when any one of the plugs is raised the corresponding contact-springs engage the contact-sleeve 22 and are thus electrically connected. To retain the plugs in

either raised or lowered position the contact-sleeves 22 are provided with grooves to engage the convex ends of the contact-springs, and the bushings 21 are similarly grooved. In order that the switch may be used, as above stated, in a three-wire system, a second pair of contact-springs 52 is arranged to coöperate with each plug. The springs 52 are constantly in engagement with a smooth cylindrical portion of the contact-sleeve 22, whether the plug be in its upper or lower position. All of the springs 52 except those coöperating with the extreme right-hand plug, are connected with a common conductor or bus-bar 51 at the back of the base-plate, and this bus-bar may be connected, by means of a terminal 53, with the neutral conductor of the three-wire system. Accordingly, when any one of the plugs is raised it not only connects the conductors attached, respectively, to the springs 45, but it also connects both of these conductors with the neutral conductor, and in this way both branches of a three-wire circuit may be simultaneously connected with or disconnected from the neutral conductor and each other.

The right-hand switch-plug, as shown in Figs. 1 and 2, is not grooved, as this plug is designed for temporary use to convey a heavy current, as, for example, in throwing an electric starting-apparatus into operation, and in the case of this plug both upper contact-springs may be connected to one conductor, and both lower contact-springs to another conductor, in the manner shown in Fig. 2.

The novel form of the locking-plate above described permits the use of the simple and inexpensive form of sheet-metal casing shown in the drawings, and thus simplifies the switch and reduces the expense of its construction, while permitting its metal parts to be made almost entirely of pressed or stamped sheet-metal.

It will be understood that although certain parts of the switch are defined, in the claims, in the spatial relation illustrated in the drawings, this description is simply for the sake of setting forth their relative arrangement, as the switch may obviously be used in various other positions without change in its construction and mode of operation.

I claim:—

1. An electric switch having, in combination, a casing provided with parallel upper and lower walls; a series of switch-plugs movable vertically through said walls and having locking-abutments; and locking-mechanisms for the plugs comprising a locking-plate having abutments coöperating with the abutments on the plugs, the locking-plate being provided with lateral flanges, projecting into engagement with one wall of

the casing, and end-portions projecting into engagement with the opposite wall, whereby the locking-plate is guided to move between and parallel with said walls.

- 5 2. An electric switch having, in combination, a seamless sheet-metal casing with parallel upper and lower walls, said walls having alining perforations; a series of switch-plugs movable vertically through said perforations and provided with locking-abutments; a locking-plate coöperating with said locking-abutments and provided with upward and downward projections, near its ends, which engage the upper and lower 10 walls of the casing so as to guide the plate for horizontal movement within the casing; contact devices coöperating with the plugs and located between the locking-plate and one wall of the casing; and means for moving the locking-plate, said means engaging 15 one of said projections thereon.
3. An electric switch having, in combination, a casing provided with parallel upper and lower walls; a series of switch-plugs 20 movable vertically through said walls and having locking-abutments near their lower ends; a locking-plate coöperating with said abutments and located near the lower wall of the casing, said plate having lateral flanges which stiffen the plate longitudinally and extend, near their ends, into engagement with the lower wall of the casing,
- 25

and upwardly-bent extremities which engage the upper wall, the front wall, and the rear wall of the casing, the plate being 30 guided by said flanges and extremities to move horizontally in the casing; means for so moving the plate to lock and unlock the plugs; and contact-devices coöperating with the plugs and located within the casing 35 above the locking-plate.

4. An electric switch having, in combination, a casing provided with upper and lower walls; a plurality of switch-plugs movable vertically through said walls and each provided with an elongated conducting-sleeve; two contact-members coöperating with each switch-plug, said members being insulated from each other and provided with separate terminals; and a third set of contact-members, which are insulated from the first-mentioned contact-members and constantly engaging the respective contact-sleeves, and are interconnected and provided with a common terminal; the three contact-members at each switch-plug being simultaneously interconnected by the contact-sleeve when the switch-plug is moved to cause the contact-sleeve to engage the first-mentioned contact-members.
